NEEDLE MOTION FOR AXMINSTER LOOMS

Application filed November 16, 1927. Serial No. 233,712.

This invention relates to needle motions for Axminster looms and it is the general object of the invention to provide a motion which will give more accurate movements to the needle to the end that the latter may be operated at a relative high rate of speed.

Axminster looms are usually provided with a weft laying needle moved into and out of the warp shed by means of a cable or rope which is wrapped around a drum. A segment and gear mechanism oscillate the drum first in one direction and then in the other to give the reciprocating movements to the needle. At the side of the loom opposite the needle motion there is customarily provided a small selvage shuttle which passes through the loop of filling at the free end of the needle. Attempts to increase the speed of wide Axminster looms have been attended with a failure on the part of the needle to register with the selvage shuttle and this is due principally to the fact that the ordinary drive for the needle permits the latter to rebound or go beyond its normal stopping position. It is an important object of my present invention to provide a metallic drive for the needle in the form of thin steel strips which are connected to both ends of the needle and are actuated by a drum.

It is a further object of my invention to provide means for giving a traverse movement to the drum so that the steel bands will be wrapped evenly around the periphery of the drum to insure precision of movement of the needle.

It is a still further object of my invention to attach the withdrawing section of the flexible actuator for the needle to the free end of the latter so that it will lie under the needle and pass into the shed to check the inserting movement of the needle.

It is a more detailed object of my invention to arrange the needle and drum so that the former moves in a path which is substantially tangential to the periphery of the drum.

With these and other objects in view which will appear as the description proceeds, my invention resides in the combination and arrangement of parts hereinafter described and set forth in the claims.

In the accompanying drawings wherein one form of my invention is shown,

Fig. 1 is a front elevation of a portion of the needle motion of an Axminster loom having my invention applied thereto,

Fig. 2 is a fragmentary top plan view 55 taken in the direction of arrow 2, Fig. 1,

Fig. 3 is an enlarged vertical section on line 3—3 of Fig. 1,

Fig. 4 is a detailed vertical section through 60 a portion of the drum showing the manner of attaching the flexible actuator thereto,

Fig. 5 is an enlarged vertical section on line 5—5 of Fig. 1, and

Fig. 6 is a detail top plan showing a modified form of attachment between the inserting flexible actuator and the needle. 65

Referring particularly to Fig. 1 it will be seen that I have provided an end frame 10 which may be secured to one of the loomsides 11 and has rotatably mounted therein driving shaft 12. An arm 13 fast with said shaft has connection with a link 14 pivoted at 15 to a rocking rack or gear segment 16 pivoted as at 17 to the frame 10. The shaft 12 rotates to rock the segment back and forth around its 75 pivot.

A needle rail 18 supported by the frame 11 is formed to guide a siding needle support 19 which may be formed as shown in Fig. 5. Said support has a dovetail extension 20 80 which slides in a slot 21 in the needle rail 18 and said support is made in two parts 22 and 23, respectively, which by means of bolts 24 may be clamped to the outer end of the needle 25. The inner end of the needle is guided by a support 26 secured to the loom-side 11 so placed as to direct the advancing end of the needle into the shed of the loom. The parts thus far described may be of common construction and form no part of my 85 present invention.

In carrying my invention into effect I provide a fixed bearing 30 secured to the frame 10 in any approved manner and mount for 95 sliding movement therein a rock shaft 31. One end of said shaft is provided with screw threads 32 which are received by a complementary threaded bearing member 33 secured by means of bolts 34 to the bearing 30. 100

A relatively small pinion 35 is secured to the rocking and sliding shaft 31 and is designed to be in mesh with the gear segment 16.

As shown more particularly in Fig. 3 the right hand end of the shaft has secured there-
 5 to a drum 36 having a hub 37 and spokes 38 which support the rim or periphery 39 of the drum. As the segment is given reciprocating movements the pinion 35 rocks first in one direction and then in the other to cause
 10 sliding or endwise movement of the shaft 31, thus carrying the drum 36 first in one direction and then in the other, the traversing movement being synchronized with the angular movement of the drum so that as the
 15 drum reverses its direction of rotation it will also change its movement in the longitudinal direction.

The means for communicating the motion of the drum to the needle include a pair of
 20 flexible and preferably sheet steel elements 40 and 41. The manner of securing these flexible members to the drum or actuating mechanism is set forth in Fig. 4, where it will be seen that the band 40 after passing around
 25 the drum extends through a slot 42 and has secured to the end thereof an adjusting screw 43 held by a lug 44 cast or in any other way made rigid with the periphery of the drum. In like manner the band 41 is provided with
 30 a screw 45 which is held in position by a lug 46. Nuts 47 on the screws 43 and 45 afford means for adjusting the bands 40 and 41 relatively to the drum.

35 As shown in Fig. 1 the band 40 extends under the needle and is secured near the advancing end thereof as at 48, while the second band 41 extends to the right of the drum as shown in Fig. 1 and is secured to the
 40 needle by means of a boss or lug 49 welded or otherwise secured to the right end of the needle as viewed in Fig. 1. The method set forth herein for securing the right end of the needle to the band 41 is but one of several
 45 constructions which may be employed and I do not wish to be held to the particular arrangement set forth herein. For instance, as shown in Fig. 6 said band 41 may be secured directly to the support 19 if desired.

50 In operation the rotation of shaft 12 will cause oscillating angular movements of the drum 36 and will also cause the latter to have reciprocating movements in the direction of the axis of shaft 31. The lead of the screw
 55 threads 32 is preferably such as will leave a slight space between successive coils of the bands 40 and 41 on the periphery of the drum, this result being accomplished by having the width of said bands slightly less than the
 60 lead of the screw. With the parts in the position shown in Fig. 1 the segment 16 will move to the right to cause a counter-clockwise rotation of the drum 36, the band 41 being wound on the drum to move the needle
 65 to the left or into the shed and the band 40

being unwound from said drum and held substantially taut during the entire inward movement of the needle so that as the latter arrives at the end of its weft inserting movement the band 40 will check the needle and prevent the same from moving beyond its proper position. Continued operation of the loom will move the segment toward the left, which will be accompanied by a tensioning of the band 40 to move the needle out of the shed and at the same time the band 41 will be unwound from the drum. At the end of the needle withdrawing movement the band 41 will act to prevent undue movement to the right. Should it be desired to vary the position of the needle relatively to its guides and the axis of the drum the screws 43 and 45 may be manipulated to place the needle in the desired position.

70 From the foregoing it will be seen that I have provided a simple driving mechanism for an Axminster loom needle wherein a band is attached to the leading end of the needle to move into the shed of the loom with the needle. As shown herein the drum is located
 75 below the needle so that the band 40 lies under said needle but I do not wish to be limited to this construction. It will further be seen that the drum has a traversing motion so that the bands 40 and 41 are wound on the periphery of said drum without overlapping and also that the band 40 which withdraws the needle serves as a check to prevent excess movement during the inserting stroke which is effected by the band 41. Furthermore, the needle is substantially tangential to the drum to give greatest effect to the inserting and withdrawing movements of the flexible bands.

80 Having thus described my invention it will be seen that changes and modifications may be made therein by those skilled in the art without departing from the spirit and scope of the invention and I do not wish to be limited to the details herein disclosed, but what I claim is:

1. In a needle motion for an Axminster loom having a rigid weft laying needle moving in a substantially fixed path to be inserted into and withdrawn from the shed of the loom, flexible actuators operatively connected one to each end of the needle, a drum to which the flexible actuators are attached, and means to simultaneously oscillate said drum about its center and move the same longitudinally of its axis.

110 2. In a needle motion for an Axminster loom having a rigid weft laying needle moving in a substantially fixed path to be inserted into and withdrawn from the shed of the loom, flexible actuating means connected to the ends of the needle, a drum to which the flexible actuating means is secured, and means to give said drum simultaneous angular move- 120
 125
 130

ments and longitudinal movements in the direction of the axis thereof.

3. In a needle motion for an Axminster loom having a rigid weft laying needle moving in a substantially fixed path to be inserted into and withdrawn from the shed of the loom, flexible actuating means operatively connected to the ends of the needle, a rotatable drum to which the flexible actuating means is attached, means to give said drum rotary motions in opposite directions, and means to reciprocate said drum along its axis of rotation.

4. In a needle motion for an Axminster loom having a rigid weft laying needle moving in a substantially fixed path to be inserted into and withdrawn from the shed of the loom, a pair of flexible actuating elements one operatively connected to each end of the needle, a rotatable drum to which both elements are attached, means to rotate said drum to cause reciprocating movements of the needle, and additional means to give said drum a traversing movement along the axis thereof.

5. In a needle motion for an Axminster loom having a rigid weft laying needle moving in a substantially fixed path to be inserted into and withdrawn from the shed of the loom, a pair of flexible flat metallic actuators one operatively connected to each end of the needle, a rotatable longitudinally movable drum to which said actuators are attached, means to oscillate said drum, and means to give said drum a traversing movement along its axis of oscillation, the needle being substantially tangential with the drum.

6. In a needle motion for an Axminster loom having a weft laying needle to be inserted into and withdrawn from the shed of the loom, a pair of flexible actuators operatively connected one to each end of the needle, an oscillating drum around which a portion of each flexible actuator is wound, and means defining adjustable connections to attach the other end of each actuator to the drum, oscillation of the latter moving the needle by means of the flexible actuators and the adjustable connections affording means for varying the position of the needle relatively to the drum.

7. In a needle motion for an Axminster loom having a rigid weft laying needle moving in a substantially fixed path to be inserted into and withdrawn from the shed of the loom, flexible actuating means operatively connected to each end of the needle, an oscillatable traversing drum to which the means is attached, a shaft on which said drum is secured, a support for said shaft, means to cause oscillation of said shaft, and means including screw threads formed on the shaft to cause traversing movement of the drum and shaft simultaneously with the oscillating movements thereof.

8. In a needle motion for an Axminster loom having a weft laying needle movable substantially in a fixed path to be inserted into and withdrawn from the shed of the loom, a drum rotatable about a fixed axis, means to move said drum along the axis as said drum rotates about the axis, flexible driving connections between each end of the needle and the drum, said drum moving transversely with respect to the path of movement of the needle.

9. In a needle motion for an Axminster loom having a weft laying needle movable substantially in a fixed path to be inserted into and withdrawn from the shed of the loom, a drum rotatable about a fixed axis, means to move said drum along the axis as said drum rotates about the axis, flexible driving connections between each end of the needle and the drum, said drum moving transversely with respect to the path of movement of the needle, and said needle for all transverse movements of the drum being intermediate the ends of the drum.

10. In a needle motion for an Axminster loom having a weft laying needle movable substantially in a fixed path to be inserted into and withdrawn from the shed of the loom, a drum rotatable about a fixed axis, means to move said drum along the axis as said drum rotates about the axis, flexible driving connections between each end of the needle and the drum, said drum moving transversely with respect to the path of movement of the needle, and means to vary the connection between the drum and the flexible means while the drum remains at rest.

11. In a needle motion for an Axminster loom having a weft laying needle movable substantially in a fixed path to be inserted into and withdrawn from the shed of the loom, a drum rotatable about the shaft extending transversely of the path of movement of the needle, said drum being also movable along its axis in a direction transversely of the needle, a pair of flexible actuators one of which is connected at its outer end to one end of the needle and the other of which is connected at its outer end to the other end of the needle, means to connect the inner ends of said flexible bands to the drum, means to vary the relation between the inner ends of the bands and the drum while the drum is at rest, and means to cause movement of the drum along its axis in timed relation with the movement of the needle along its path.

12. In a needle motion for an Axminster loom having a weft laying needle to be inserted into and withdrawn from the shed of the loom, a pair of flexible actuators operatively connected one to each end of the needle, an oscillating drum around which a portion of each flexible actuator is wound,

said drum having an outer rim around which the element is wound and having an opening therein through which the flexible element passes to become operatively attached to the drum.

5 In testimony whereof I have hereunto affixed my signature,

ELBRIDGE R. HOLMES.
